UNITED STATES PATENT OFFICE.

EDWARD HIRT, OF WEYMOUTH, MASSACHUSETTS.

PORTABLE ELECTRIC-ARC LIGHT.

1,371,420.

Specification of Letters Patent. Patented Mar. 15, 1921.

Application filed January 2, 1917. Serial No. 140,014.

To all whom it may concern:

Be it known that I, EDWARD HIRT, a citizen of the United States, and a resident of Weymouth, in the county of Norfolk and 5 State of Massachusetts, have invented an Improvement in Portable Electric-Arc Lights, of which the following description, in connection with the accompanying drawings, is a specification, like characters on the 10 drawings representing like parts.

This invention relates to electric arc lamps and has for its object to provide a portable arc lamp capable of being carried in one hand and especially adapted among other 15 uses to be employed for furnishing the light necessary for making blue prints, photo-prints and the like.

To this end, the electrodes or carbon pencils are secured in holders of slate or other 20 insulating material, which are fastened to a supporting frame comprising two members, preferably pivoted together so as to be capable of adjusting the carbons as they are consumed, and which frame is capable of 25 being carried in one hand and moved over the glass beneath which the blue print paper is placed. The electrodes are connected with a suitable switch, preferably a plug switch capable of being inserted in the ordinary 30 incandescent lamp socket, and between the electrodes and said plug switch is a resistance coil which may and preferably will be used as a heater for drying the blue prints.

35 These and other features of this invention will be pointed out in the claims at the end of this specification.

Figure 1 represents a portable arc lamp embodying this invention, and

40 Fig. 2, a side elevation looking toward the left in Fig. 1.

Referring to the drawings *a*, *b*, represent two arms or members preferably of wood or other insulating material and curved at 45 their inner ends, and preferably mounted to turn on a pivot pin *c*, so as to adjust the carbon or other suitable pencils 10, 12, toward and from each other.

The arms *a*, *b*, may be secured in their adjusted position by a thumb nut 13 engaging the pivot *c*, and adapted to frictionally clamp the said arms together in a manner well understood.

The arms or members *a*, *b*, carry at their 55 outer ends holders for the carbon pencils 10,

12, which holders may be of like construction and each of which consists as herein shown of a stationary member 14, see Fig. 2, of slate or other insulating material and a movable member 15 of like material, between which the carbon pencil is clamped by a screw 16 extended through the members 14, 15, of the holder and through the arm to which said members are secured. 60

The stationary member 14 has secured to 65 it a terminal block 17 of metal or other conducting material, which is preferably provided on its upper surface with a transverse recess, preferably curved to conform to the circular form of the carbon pencil, and the 70 said block may be secured on the member 14 of the holder in any suitable manner, as by providing the block 17 with a threaded rod 20 which is extended through the member 14 and the arm *a* or *b* to which said member is secured, and is engaged by a suitable 75 nut 21.

The terminal blocks 17 are electrically connected by insulated wires 22, 23, with the terminals of a switch, preferably a plug 80 switch 24 of known construction, which is adapted to be screwed into the socket of an incandescent lamp fixture (not shown), and one of the wires as 22 has included in it a resistance coil 25, which reduces the 85 strength of the current flowing to the carbon pencils and which also acts as a heater to dry the blue print or other similar paper after it has been washed. The resistance coil 25 is of known construction and is mounted on a 90 center pin 26, which is supported by a suitable frame preferably of sheet metal, which is shaped to form substantially parallel end walls 28 on which the pin 26 is supported, and a top wall 29, which is preferably provided with perforations 30 and upon which the wet blue print paper may be laid to dry, or said paper may be supported above the 95 heater upon bent rods 31, 32, which are pivoted to the opposite sides of the end walls 100 and are made of such size as to project above the top wall of the heater. The pivoted rods 31, 32, are capable of being moved toward and away from each other, so as to form an adjustable support for sheets of 105 print paper of various sizes within limits, and also to serve as handles for carrying the heater. The end walls 28 may be provided with outwardly extended flanges 34 to form feet for the heater. 110

The carbon pencils 10, 12 may have co-operating with them a reflector 35, which is secured to a rod 36, rotatably mounted in a post 37, secured to one of the arms as *a*, and 5 said rod may be secured in its adjusted position in said post by the frictional fit of said rod or in any other suitable manner. The wires 22, 23, may and preferably will be laid in grooves 38 in the outer sides or edges of 10 the arms and secured therein against displacement in any suitable manner.

In operation with the apparatus herein shown, the plug 24 is inserted in the lamp socket and the arms *a*, *b*, are moved toward 15 each other until the carbons 10, 12, are brought into contact with each other. The current is then turned on, and if desired the carbons may be allowed to burn until the 20 arc is of the proper length or the arms *a*, *b*, may be moved away from each other to draw the arc. The reflector 35 is turned with relation to the arc so as to deflect the light 25 down upon the glass of the blue print frame (not shown) but which may be such as commonly used, and when the light is of the desired intensity, the supporting frame *a*, *b*, is held by one hand of the operator and moved over the glass, thereby exposing the blue 30 print paper to the action of the light to print the same, after which the print is removed, washed in the usual manner to develop it, and then placed on the heater to dry. The apparatus is especially adapted to be used by draftsmen in small concerns, offices and 35 like places, and especially on dark days, and is a compact, inexpensive and highly efficient arc light for the purpose of taking blue prints, photoprints and the like, and when not in use can be detached from the lamp 40 socket and stored away in a small space. It will be observed that the light can be extinguished by merely separating the carbons

to break the arc, thereby avoiding the use of a separate switch for this purpose.

I have herein shown one construction of 45 apparatus embodying the invention, but it is not desired to limit the invention to the particular construction shown although it may be preferred.

Claims:

1. A portable arc light comprising a supporting frame consisting of arms having curved inner ends pivoted together and capable of being grasped by a hand of the operator and moved toward and from each other by the hand in which they are held, means coöperating with said pivot to frictionally secure said arms in their adjusted positions, carbon holders of insulating material secured to the free ends of said arms 55 to move therewith, carbon pencils carried by said holders and extended toward each other between said arms, and conductors carried by said arms and connected with said pencils.

2. A portable arc light comprising a supporting frame consisting of arms having curved inner ends pivoted together and capable of being grasped by a hand of the operator and moved toward and from each other by the hand in which they are held, 60 means coöperating with said pivot to frictionally secure said arms in their adjusted positions, carbon holders comprising stationary and movable members of insulating material secured to the said arms near the 65 free ends of the latter, carbon pencils clamped between the members of the carbon holders and extended toward each other, and conductors carried by said arms and connected with the stationary members of said 70 carbon pencils.

In testimony whereof I have signed my name to this specification.

EDWARD HIRT.
